US0D1085818S

(12) **United States Design Patent** (10) **Patent No.:** **US D1,085,818 S**
(45) **Date of Patent:** **** Jul. 29, 2025**

(54) **CONTAINER**

(71) Applicant: **Pacific Market International, LLC**,
Seattle, WA (US)

(72) Inventor: **Ryan Michael Smith**, Seattle, WA (US)

(73) Assignee: **Pacific Market International, LLC**,
Seattle, WA (US)

(**) Term: **15 Years**

(21) Appl. No.: **29/886,618**

(22) Filed: **Mar. 10, 2023**

(51) **LOC (15) Cl.** **07-01**

(52) **U.S. Cl.** **D7/509**
USPC **D7/509**

(57) **CLAIM**

The ornamental design for a container as shown and described.

DESCRIPTION

FIG. 1 is a top perspective view of a container in a condition of use.

FIG. 2 is another top perspective view of the container of FIG. 1

FIG. 3 is a bottom perspective view of the container of FIG. 1.

FIG. 4 is a front view of the container of FIG. 1.

FIG. 5 is a back view of the container of FIG. 1.

FIG. 6 is a right side view of the container of FIG. 1.

FIG. 7 is a left side view of the container of FIG. 1.

FIG. 8 is a top view of the container of FIG. 1; and,

FIG. 9 is a bottom view of the container of FIG. 1.

The broken lines shown in FIG. 1 depict environmental subject matter and form no part of the claimed design. The remaining broken lines in the Figures depict portions of the container that form no part of the claimed design.

1 Claim, 9 Drawing Sheets
